UNITED STATES PATENT OFFICE

2,544,828

LEAKPROOF CONSTRUCTION OF PIPES,
TANKS, AND THE LIKE

Curzon Dobell, New York, N. Y., assignor to Pre-load Enterprises, Inc., a corporation of Delaware

Application May 12, 1944, Serial No. 535,353

5 Claims. (Cl. 72—14)

1

This invention relates to an improved construction of leakproof pipes, tanks, poles, piles and the like particularly adapted to convey, store or exclude liquid and gaseous fluids and, while the invention is particularly applicable to cementitious constructions, it is also wholly adaptable to considerably wider applications employing other materials. The primary requirement of structures of this nature is that they shall be and remain leakproof against the escape of the contained fluids and one object of my invention is to provide a novel and improved structure of this nature which not only fulfills this requirement but which also is adapted to be manufactured at great convenience and with minimum requirements and expense.

In its preferred form, my invention contemplates a pipe, tank or the like incorporating a flexible leakproof diaphragm within its wall constructed from a ribbon of liquid-impervious material wrapped in helical overlapping relation within the wall and forming therein and therewith a barrier to the passage of fluids and moisture. I am aware that structures of this nature incorporating cylindrical metallic diaphragms, as in Mitchell Patent 2,031,057, have been heretofore proposed but a structure incorporating a diaphragm formed by wrapping tightly thereonto in overlapping relation a liquid-impervious ribbon is new as far as I am aware. The production of an improved leakproof construction of this nature comprises another object of the invention.

Pipes, tanks and like containers, usually of cementitious construction as in Patents 2,031,057 and 2,315,894, have heretofore been placed and held under a predetermined compression by being wrapped with round wire under tension and the wire wrapping has been thereafter covered with a bonding layer of concrete, all for the purpose of preventing the wall from expansion cracking and thus maintaining it against leakage. A further and very important feature of my invention contemplates the wrapping of these structures with flat or ribbon wire in overlapping relation and tensioned to place the structure under the required compression, the overlapped wrapping not only serving the prestressing function but furthermore providing a continuous diaphragm within and extending about the structure. While the ribbon employed will ordinarily be relatively thin and flexible, as steel of safety razor blade thickness, whereby it will under tension make close contact at the overlapping joints, it may be desirable in some cases to provide a suitable sealing material at such joints, all as hereinafter

2

more fully described. Furthermore, since round wire is more economical than flat ribbon wire it may in some cases be desirable to use round wire in association with ribbon stock to provide the required prestressing strength and permit considerable savings in the amount of flat stock required and my invention contemplates the combining of these two types of reinforcement. In any case, the final wrappings will preferably be covered and sealed within a coating of suitable material which can be of a cementitious nature or of a liquid plastic or paint-like composition. The production of such an improved construction for the purpose described comprises a further object of the invention.

These and other features of the invention will be best understood and appreciated from the following description of preferred embodiments thereof selected for purposes of illustration and shown in the accompanying drawings in which,

Fig. 1 is a fragmentary plan sectional view of a tank embodying my invention.

Fig. 2 is a fragmentary view showing the tank in vertical section,

Fig. 3 is a fragmentary front elevation with portions broken away,

Fig. 4 is a view like Fig. 2 but illustrating a modification,

Fig. 5 is a front elevation illustrating another form of the invention,

Fig. 6 is a vertical view taken on line 6—6 of Fig. 5,

Fig. 7 is a fragmentary front elevation partially broken away and illustrating a further modified form of the invention,

Fig. 8 is a vertical section taken on line 8—8 of Fig. 7,

Fig. 9 is a fragmentary front elevation of a modified construction.

Referring first to Figs. 1—3 of the drawings, 10 indicates the wall of a tank illustrated as formed by projecting liquid cementitious composition onto a form 12, as in Patent 2,315,894. The primary purpose of the tank is to contain liquids and the patented tank is banded circumferentially by rods in tension placing the tank under compression whereby preventing cracking of the concrete and resultant leakage. My invention contemplates the circumferential banding of the wall 10 by a

ribbon 14 of liquid impervious material wrapped in helical overlapping relation onto and about the outer face of the tank wall and in tight contact at the overlapping joints whereby forming a continuous diaphragm over said face. The ribbon will preferably be of high tensile strength and

applied under tension placing the tank walls under compression, sheet steel of safety razor blade thickness being preferred although other metals and suitable plastics in ribbon form are adapted to the forming of a continuous leak-proof diaphragm.

The adjacent convolutions of the ribbon are overlapped at 16 and in any event will be under sufficient tension to bring and hold the overlapping faces in firm contact. Also the overlapping will ordinarily be greatest at the bottom where the liquid pressure is greatest and may gradually diminish upwardly. In the preferred form of the invention, steel ribbon is employed and it is wrapped onto the tank wall under a tension placing the wall in compression as in said patent, the ribbon thereby serving the two functions of (1) prestressing the tank as is done by the banding wire or rods in said patent and (2) providing a continuous diaphragm on and covering the wall. Following the banding operation, the diaphragm is preferably covered with a coating 18 of waterproofing material. This coating can be a cementitious composition or a plastic or paint applied pneumatically or with a brush. In its complete form the wrapped ribbon provides a diaphragm within the wall and serves the functions of reinforcing the wall, forming a barrier to the escape of fluids through the wall, and preferably holding the wall under a predetermined compression.

The waterproof coating 18 bonds tightly to the diaphragm and prevents the contact of air or moisture therewith whereby maintaining the diaphragm against rust and deterioration. It may also be desirable in some cases to provide a coating on the inner face of the diaphragm for the same purpose. This coating can be applied to the ribbon as the latter is applied to the wall or suitable coating material can be applied to the wall in advance of the ribbon. In Fig. 4 I have illustrated the wall as provided with a coating 29 of plastic preservative preferably of a bituminous nature. The ribbon 22 as applied to the wall directly contacts this coating which forms a rust preventative against the inner face of the diaphragm and also aids in providing a tight seal at the joints. The ribbon is otherwise applied and covered in the manner above described in connection with Figs. 1-3.

While, as above described, the ribbon will be applied under sufficient tension to form a firm contact at the overlapping areas it may be desirable in some cases to provide a suitable material between the convolutions at the overlapping joints to form a moisture-proof seal. Such material will preferably be of a nature to bond or seal to the overlapping faces and can comprise suitable paint, plastic, solder, sulfur or like compositions capable of forming a sealed joint. A plastic known as "Tygon" has the property of bonding to and forming a strong sealing joint between overlapped steel surfaces which are held together under pressure during the setting of the "Tygon" coating. The "Tygon" or other bonding material employed will preferably be applied to the overlapping area of one or both surfaces of the ribbon as the latter is being applied to the wall so as to sandwich a coating of the material between the overlapping surfaces. The surfaces are thereafter held together under pressure as above described.

In Fig. 5 I have illustrated the application of a coating 30 of solder, sulfur or like fusible material to the overlapping area of one face of the

ribbon 32 as the latter is wound onto the wall 34. The ribbon is wrapped in the direction of the arrow and heat is applied progressively to the outside of the ribbon at the coated area as the wrapping progresses. The heat can be conveniently applied by contacting a hot iron and moving it along the ribbon in the direction of the arrow as indicated at 36. The heat is adapted to fuse the coating and effect a firm and tight bond at the joint.

It will be apparent that when the ribbon is to provide a substantial compression of the wall it must have relatively more overlap, as illustrated in Figs. 2 and 3, and it will be apparent that this requires the use of a relatively greater amount of ribbon stock. Such stock is more expensive than round wire and for this reason it is desirable in some cases to combine the use of both ribbon stock and round wire, the former providing a diaphragm and part of the compression and the latter providing the balance of the required compression. In Figs. 7 and 8 I have illustrated this combination. The wall 40 is first wrapped with the ribbon 42 with sufficient overlap to provide the continuous diaphragm, and one or more wrappings of round wire 44 are thereafter applied all under a tension placing the tank under the required compression. The wrappings are thereafter covered with a coating 46 in the manner above described. It will be apparent that such construction effects substantial savings since it employs a substantial amount of the cheaper round wire in lieu of the more expensive ribbon. While I have illustrated the wrappings of the round wire over and onto the diaphragm, I desire it to be understood that the construction can employ the use of the round wire directly onto the wall, the ribbon stock being thereafter wrapped about and covering the round wire convolutions.

While the ribbon stock will preferably be wrapped in one continuous piece helically and in overlapping relation, as above described, it is possible to use independent bands 50 and wrap them consecutively into overlapping relation to provide a continuous diaphragm, as illustrated in Fig. 9. In such construction, each band will be tensioned tightly onto the wall and its two ends will be brought and secured in overlapping relation by riveting, soldering or in any convenient manner, as illustrated at 52.

I have herein illustrated and described only certain forms and features of the invention and it will be understood that such specific disclosure is presented only by way of example, the scope of the invention being determined by the claims appended hereto. It is especially noted that, whereas I have herein illustrated and described my invention in connection with a tank, the invention is by no means limited thereto nor to any specific object, shape or material. The wall of the tank or pipe to which the ribbon is applied is of annular configuration in the sense that it is continuous but not necessarily circular.

Having now described and illustrated my invention, what I claim as new and desire to secure by Letters Patent of the United States is:

1. A cylindrical container comprising an annular wall of a thickness to sustain substantial compression, and ribbon stock of liquid-impermeable material of high tensile strength wrapped in overlapping relation about and under substantial tension in contact with the outer face of the wall and forming a continuous diaphragm over

and enclosing said face and placing the wall in prestressed compression.

2. A cylindrical container comprising an annular wall of a thickness to sustain substantial compression, a ribbon of liquid-impervious material of high tensile strength wrapped in helical overlapping relation about and under substantial tension in contact with the outer face of the wall and forming a continuous diaphragm over and enclosing said face and holding the wall in compression, and sealing means between the overlapping faces of the ribbon.

3. A cylindrical container comprising an annular wall of cementitious material, and a relatively thin steel ribbon of high tensile strength wrapped in helical overlapping relation about and under substantial tension against the outer face of the wall and forming a continuous diaphragm over and enclosing said face and placing the wall in prestressed compression.

4. A cylindrical container comprising an annular wall of a thickness to sustain substantial compression, a ribbon stock of liquid-impervious material of high tensile strength wrapped in overlapping relation about and under substantial tension in contact with the outer face of the wall and forming a continuous diaphragm over and enclosing said face and placing the wall in prestressed compression, round wire under substantial tension wrapped helically over the dia-

10 phragm and increasing said prestressed compression, and means providing a cover coating over the wire and diaphragm.

5. A cylindrical member of cementitious material having a cylindrical outer face, a steel ribbon of high tensile strength wrapped in helical overlapping relation under substantial tension on said face about the member and forming a continuous diaphragm thereon enclosing the member at said face and placing the member in prestressed compression, and a sealing cover of plastic material over the diaphragm.
